[57] CLAIM

The ornamental design for an insulator for an open coil electric heating unit, substantially as shown.

DESCRIPTION

FIG. 1 is a front elevational view of an insulator for an open coil electric heating unit, showing my new design;
FIG. 2 is a rear elevational view thereof,
FIG. 3 is a side elevational view thereof,
FIG. 4 is a cross sectional view taken on line 4—4 of
FIG. 1,
FIG. 5 is a front perspective view thereof, and
FIG. 6 is a rear perspective view thereof.

FIG. 1.

FIG. 2.

FIG. 3.

FIG. 4.

FIG. 5.

FIG. 6.
